CONTINUOUS MINING APPARATUS OF THE CHAIN TYPE FOR LONGWALL MINING

John A. Russell and Joseph R. Bouille, Sydney, Nova Scotia, Canada, assignors to Joy Manufacturing Company, Pittsburgh, Pa., a corporation of Pennsylvania

Filed Oct. 3, 1952, Ser. No. 312,876

12 Claims. (Cl. 262—29)

This invention relates to a mining apparatus and more particularly to an improved mining and loading machine especially designed for use in the mechanical mining of coal from a solid coal seam in accordance with the longwall system, and for loading the dislodged coal as mining progresses.

The present invention resides in improvements over those of the longwall continuous miner disclosed in a co-pending application, Serial No. 131,094, filed December 5, 1949, now Patent No. 2,721,067, owned by applicants' assignee. The improvements of the present machine reside primarily in a well balanced design which provides greatest stability in operation and embodying a disintegrating head having a novel arrangement of the orbitally movable disintegrating elements whereby coarser coal may be mined out. The novel head structure embodies an improved arrangement of the endless disintegrating chains, improved guides therefor and improved individual adjusting devices for the chains for adjusting the chain tension. An improved power swinging arrangement is associated with the head providing not only compactness but extreme ruggedness in design. Further, the major elements of the improved machine are arranged in an improved and extremely compact manner and made readily accessible to facilitate inspection and maintenance. The machine is not only relatively compact but is also readily maneuverable and highly efficient, well adapted for its intended purpose.

It is therefore a primary object of the present invention to provide an improved mining and loading apparatus having improved features of construction. Another object is to provide an improved disintegrating head mechanism for a continuous mining apparatus, having improved swinging means for the head. A further object is to provide an improved chain type disintegrating head having improved guiding and adjusting means for the disintegrating chains. A still further object is to provide improved tensioning adjusting devices individual to each disintegrating chain. Yet another object is to provide an improved continuous mining apparatus especially designed for use in accordance with the longwall system of mining and having a novel and compact arrangement of parts. These and other objects and advantages of the invention will, however, hereinafter more fully appear.

In the accompanying drawings there is shown for purposes of illustration one form which the invention may assume in practice.

In these drawings:

Fig. 1 is a plan view of the improved continuous mining apparatus.

Fig. 2 is a side elevational view of the apparatus shown in Fig. 1.

Fig. 3 is a central longitudinal vertical sectional view taken on line 3—3 of Fig. 1.

Fig. 4 is an enlarged cross section taken on line 4—4 of Fig. 3.

Fig. 5 is an enlarged horizontal sectional view taken

2

on line 5—5 of Fig. 2, with parts shown in plan and with other parts omitted, to facilitate illustration.

Fig. 6 is a cross section taken on line 6—6 of Fig. 5.

Fig. 7 is a detail longitudinal vertical section taken on line 7—7 of Fig. 5.

Fig. 8 is a detail longitudinal vertical section taken on line 8—8 of Fig. 5.

Fig. 9 is a sectional view taken on the plane of Fig. 7, showing an adjusting wrench attached to the adjusting screw for one of the chain adjusting devices.

Fig. 10 is an enlarged longitudinal vertical section taken on the planes of line 10—10 of Fig. 5.

Fig. 11 is a detail section taken on line 11—11 of Fig. 10, illustrating details of the head swing cylinder devices.

Fig. 12 is a diagrammatic view illustrating the hydraulic system.

Fig. 13 is a diagrammatic horizontal sectional view showing the improved continuous miner in its operating position at the longwall face of a mine.

Fig. 14 is a diagrammatic vertical section showing the continuous miner in operating position in a mine and illustrating the different positions of the disintegrating head.

In this illustrative embodiment of the invention, as shown in the drawings, the improved mining and loading

apparatus or so-called continuous miner, generally comprises a mobile base 1, desirably a crawler base, adapted to travel over the floor or pavement of a mine and carrying a frame 2 providing longitudinal guides 3 on which a support 4 is slidably guided for rectilinear longitudinal movement with respect to the base frame. Pivotally mounted on this sliding support 4, at 5, is a coal disintegrating mechanism or so-called disintegrating head generally designated 6, to swing in vertical planes with respect to the sliding support and base frame, and swing cylinder devices 7 are associated with the head for swinging the latter about its pivot and for holding the same in its different positions of adjustment about the head axis. A transverse conveyor 8 is carried by the sliding support 4 rearwardly of the head pivot for receiving the

coal dislodged and disintegrated by the head and for conveying the disintegrated coal laterally to discharge at one side of the machine. A pair of motors 9, desirably electric motors, are mounted at the opposite sides of the rearward portion of the base frame 2 and these motors are operatively connected by a universal telescopic drive shafting 10 to the disintegrating head for driving the disintegrating elements 11 thereof. A motor 12 arranged on the base frame 2 intermediate the motors 9, and likewise desirably an electric motor, drives pumping means, later described, for supplying liquid under pressure to the various hydraulically operated devices of the machine.

The crawler base 1 has usual tread frames 14 mounted at the opposite sides of the base frame 2, and endless crawler treads 15, driven by independent reversible, variable speed hydraulic motors or engines, are guided for orbital circulation about guideways provided by the side tread frames, and these treads may be simultaneously or independently driven in a conventional manner to effect propulsion and steering of the machine as the latter travels over the floor or pavement.

Now referring to the specific structure of the coal disintegrating head 6, it will be noted that a swingable head or jib frame 16 (Fig. 5) has a series of laterally spaced, vertical bearing-engaging portions 17 at its rear pivoted end, and the sides of the head frame are pivotally supported on side gear casings or housings 18 carried at the outer sides of the sliding support 4 and the bearing-engaging portions are pivotally supported on the hubs of driving sprockets 19 in turn supported by and keyed to a cross shaft 20 axially aligned with the head pivot 5, and this cross shaft is in turn journaled in bearings 21 supported within the gear housings 18. The sprockets 19

engage and drive the disintegrating elements 11 which herein assume the form of endless disintegrating chains as later explained. The shaft 20 has keyed to its opposite ends worm wheels 22 whose hubs are mounted in the bearings 21, in the manner shown. The drive for the disintegrating chains may be generally similar to that disclosed in the copending application, Serial No. 131,094 above referred to, and, as in this pending application, the worm wheels are driven by worms 23, shown in dotted lines in Fig. 2. These worms are fixed to parallel longitudinal shafts 24 which are connected through intermeshing spur gearings 25 and conventional flexible couplings 26 to the universal telescopic shaftings 10. The shafts 24 are suitably journaled within the sliding support 4 while the shaftings 10 are suitably journaled within bearings supported by the base frame 2. Thus, the disintegrating chains 11 may be continuously driven during running of the motors 9 irrespective of the position of the sliding support 4 along its guides longitudinally relative to the base frame and irrespective of the position of the disintegrating head about its pivotal axis.

The disintegrating head is formed with a series of chain guideways 30, herein desirably seven in number and provided in part by guides 32 secured to the top and bottom of the head frame. The portions 30^a of these chain guideways at the forward portion of the head are formed on a front adjustable frame portion or nose 31 of the head or jib frame, and these forward portions of the guideways are parallel and extend in longitudinal vertical planes, and the central guideway along its entire length is parallel to the longitudinal median line of the machine, while the three guideways at each side of the central chain extend for substantial portions of their length, at 30^b along relatively inclined lines which converge rearwardly toward the central longitudinal vertical plane of the machine. The rearward portions 30^c of these guideways are parallel with the forward portions but lie closer together, as shown in Figs. 1 and 5, so that the rear pivoted end of the disintegrating head is substantially narrower than its effective forward coal-engaging portion. In other words, the side disintegrating chains extend along lines which diverge forwardly and outwardly from the pivoted end of the disintegrating head, providing a relatively wide effective forward head portion which is at least as great in width as the width of any other portion of the machine, thus enabling the head to remove a vertical segment of coal from a solid coal seam, in a manner to be later described, to provide a passageway in the seam of sufficient size to receive the machine as mining progresses.

The adjustable forward or outer nose portion 31 of the head or jib frame is guided for adjustment longitudinally relative to the rearward head frame 16 in a direction extending radially of the head pivot axis to obtain a certain degree of simultaneous tensioning of all seven disintegrating chains, and parallel longitudinally extending guide rods or bars 33 secured at 34, as by welding, to the sides of the adjustable frame portion or nose 31 and guided in bores formed in lateral guide portions 35 integral with the sides of the rearward head frame 16, serve to guide the forward nose portion during such adjustment. Adjusting screws 36 are journaled at 37 on projections 38 integral with the rearward head frame and these screws have threaded portions received in threaded openings 39 in the guide rods 33. The screws 36 have enlarged annular turning collars 40 formed with suitable radial openings for the reception of a conventional turning bar or wrench insertable therein from the exterior of the head frame. As shown in Figs. 5 and 8, coal guide members or bars 41 are arranged between the upper chain guideways at the top of the jib and provide wall portions at the opposite sides of the central guideway and the next two outer guideways at opposite sides of the central guideway for guiding the disintegrated coal as it is moved rearwardly by the chains, and the outermost two of the coal guide members 41 provide inner guide walls at the

outermost chain guideways while outer guide wall portions are formed on guide members 42 rigidly secured to the rearward head frame 16 at the remote sides of the head. Obviously, if desired, the outermost guide members 42 may be adjustable laterally relative to the rearward head frame. The six coal guiding and directing members 41 are pivotally secured at their rearward ends by screws 43 to the head frame and are in substantial alignment with rear guide sections 44 rigidly secured by screws 45 to the rearward head frame. The forward end portions of the guide members 41 are longitudinally slotted at 46 and screws 47 pass through these slots and are threaded within openings 48 in the adjustable frame portion or nose 31. It will therefore be evident that when the front screws 47 are loosened and the outer frame portion 31 is adjusted longitudinally along its guides relative to the rearward head frame 16 the coal guiding and directing members 41 will swing slightly in common transverse planes at the top of the head frame about their rear screws 43 to change the inclination of these guiding and directing members with respect to the chain guideways. After adjustment of these guide members, if desired, the screws 47 may be tightened to hold the parts firmly in position. It will thus be evident that as the outer head portion 31 is adjusted along its guides relative to the rear frame the angular relation of the guide members 41 with respect to the portions 30^a of the upper chain guideways is varied slightly, so that the loose coal being conveyed by the upper runs of the disintegrating chains is always properly directed rearwardly and inwardly toward the cross conveyor.

In addition to the adjustment provided by the adjustable outer head or nose frame 31 there are provided individual adjustments for the seven disintegrating chains. Each guideway portion 30^a is formed in a sliding block or nose piece 52 (Figs. 5 and 6) adjustable longitudinally in parallelism with the path of adjustment of the outer head portion 31, and each of these blocks has longitudinal guideways 53 at its sides for receiving longitudinal guides 54 rigidly secured as by rivets to vertical narrow plate-like portions 55 integral with the frame portion 31. Extending longitudinally in each block is an adjusting screw 56 threadedly engaged in openings 57 in the blocks and these screws when rotated effect longitudinal adjustment of the blocks 52 along their guideways relative to the head frame portion 31. First referring to the shorter adjusting screws 56^a for the outermost blocks 52 at the remote sides of the head, it will be noted that the screws are arranged in openings 58 in the blocks and have annular flanges 59 which are held rotatably against the nose frame 31 by a retaining ring 60 cooperating with the screw flange for holding the adjusting screw against axial movement with respect to the frame portion 31. The intermediate screws 56^b are somewhat longer than the side screws 56^a and are arranged in openings 61 in the blocks or nose pieces 52 and have annular flanges 62 (Fig. 7) at their rear ends and are rotatably held in position against axial movement with respect to the frame portion 31 by retaining rings 63 secured to the frame portion and engaging the screw-flange. There are seven adjusting screws provided, one for each of the seven chain guideways, and the adjusting screws extend the same distance forwardly and each has a polygonal recess 64 for receiving a conventional Allen wrench. Aligned with and communicating with the openings which receive the adjusting screws are threaded openings 65 which receive screws 66. During adjustment of the sliding blocks the screws 66 are removed from the openings 65 and the Allen wrench, designated 67 in Fig. 9, may then be inserted through the opening 65 to bring its polygonal end into engagement with the screw recesses 64 so that the screws may be rotated to effect adjustment of the blocks or nose pieces 52. After the blocks 52 have been properly adjusted the wrench may be removed and the

screws 66 reinserted in the opening 65 and adjusted inwardly into abutting engagement with the adjusting screws to lock the parts in adjusted position. As shown in Figs. 7 and 9 the adjusting blocks or nose pieces 52 have semi-circular forward end surfaces 68 so that as the disintegrating chains are circulated orbitally within their guideways in the head frame the lower runs of the chains leave the bottom portions of the guideways and pass around the semi-circular end surfaces of the jib nose so as to direct the upper runs of the chains rearwardly toward and into the chain guideways at the top of the head or jib frame.

The disintegrating chains 11 may assume any suitable form but herein desirably are of the universal ball and socket type comprising a series of chain blocks 70 universally pivotally connected together by ball and socket joint connections 71 and these chain blocks have lateral lugs 72 formed with sockets for receiving conventional disintegrating teeth or bits 73 held in position by usual set screws 74 (Figs. 7 and 9). These chains cut out parallel slots in the coal to provide cores or projections of coal between the slots and each chain carries core breaker bits for breaking away the cores. As shown most clearly in Fig. 9 each of the chain blocks 70 is formed with an opening 75 to permit the passage of the Allen wrench through the chain into position to effect adjustment of the block adjusting screws in the manner explained above. These disintegrating chains may be generally similar in design to that disclosed in United States Patent No. 2,566,675 granted September 4, 1951. As mentioned above the particular structure of the disintegrating chains does not per se enter into the present invention and any suitable type of universal chain may be employed in lieu of that disclosed herein.

Secured in a suitable manner to the remote sides of the upper portion of the head frame are upstanding deflector plates 80 which cooperate to provide a troughlike passageway through which the disintegrated coal is moved rearwardly by the top runs of the disintegrating chains and cooperating with these deflector plates are side deflector plates 81 on the tops of the gear casings 18 for deflecting the loose coal rearwardly toward the cross conveyor 8. A rearwardly and downwardly inclined transverse bottom plate 82 serves to direct the flow of the loose coal rearwardly and downwardly toward the upper run of the conveyor, as shown in Fig. 3.

Now referring to the head swinging mechanism, it will be noted that the swing cylinder devices 7 are arranged at the opposite sides of the rearward narrow portion of the head. These cylinder devices are desirably of the double telescopic type and comprise outer cylinders 85 pivoted on transverse pivot pins 86 to swing in longitudinal vertical planes, and these pivot pins are supported in spaced parallel forward projections 87 integral with the forward portion of the sliding support 4. As shown in Figs. 10 and 11 each outer cylinder 85 has parallel front and rear bores 88 which contain reciprocable pistons 89 integral with the parallel upstanding cylinders 90. Reciprocable in the bores of the cylinders 90 are pistons 91 having piston rods 92 rigidly secured at 93 at their upper ends to a cross member or yoke 94. These yokes are pivotally connected to cross pivot pins 95 supported at the outer sides of the rearward head frame 16 (see also Fig. 2). Thus, when liquid under pressure is supplied to the lower ends of the bores of the outer cylinders, the pistons 89 and 91 are moved upwardly to effect swinging of the disintegrating head in vertical planes upwardly about its pivot 5, and when liquid is trapped in these cylinder bores the disintegrating head is firmly locked in adjusted position. By venting liquid from the cylinder bores the head may swing downwardly at a controlled rate. The arrangement of pairs of cylinders arranged side by side in longitudinal vertical planes greatly reduces the lateral dimensions of the swing mechanism so that much less width is required than would be necessary if

single large cylinders were employed, and the telescopic cylinder and piston arrangement provides a wide range of swing with relatively great compactness. A bottom passageway 96 is suitably connected to the larger cylinder bores beneath the pistons and a suitable valve 97 serves to permit rapid lowering of the head. The large cylinder bores at the upper sides of the pistons 89 have port connections 98 connected by conduits 99 with small liquid tanks 100 (Fig. 11) so that as the pistons move upwardly, liquid is forced out of the upper ends of the cylinder bores and when the pistons are lowered liquid is drawn into the cylinder bores. Such an arrangement maintains liquid in the upper ends of the cylinder bores at the upper sides of the pistons while keeping out dust and dirt.

15 The cross conveyor 8 is reversible and may discharge from either side of the machine and is driven by a reversible hydraulic motor 106 (Figs. 3 and 12).

Arranged longitudinally of the base frame 2 are parallel double acting hydraulic cylinders 128 (see Fig. 3) 20 which contain reciprocal pistons (not shown) having forwardly extending piston rods 130 pivotally secured at their forward ends at 131 to brackets 132 secured to the sliding support 4. By properly supplying liquid under pressure to these cylinders the disintegrating head 25 may be moved forwardly relative to the base to effect sumping at the floor level and may be retracted from the face at the roof level as later explained. Also arranged at the opposite sides of the base frame at the front end of the latter are vertical floor jack cylinders 133 (see 30 Figs. 2 and 3) and at the opposite sides of the rearward portion of the base frame are vertical floor jack cylinders 134, and the pistons of these jacks may be lowered into engagement with the floor to tilt the base frame to direct the disintegrating head at the desired angle during the sumping operation and to hold the base steady during the disintegrating operation. Under certain conditions a vertical holding column 135 (Fig. 12) may be mounted at the rear end of the base frame and has its pistons movable into engagement with the floor and 40 roof to secure the base in position during operation of the machine on a relatively steep incline. Of course, under operating conditions where the floor or pavement is substantially level this holding column may be omitted.

Now referring to the hydraulic system on the machine shown diagrammatically in Fig. 12, it will be noted 45 that the pumping means driven by the motor 12 comprises dual or twin pumps 143 and 144 connected to the front end of the motor and a small pump 145 connected to the rear end of the motor. A liquid tank 146 is 50 mounted on the base frame rearwardly of the cross conveyor 8, as shown in Fig. 3, and these twin pumps have their suction sides connected by conduits 147 and 148 to the tank while the suction side of the pump 145 is connected to the tank by a conduit 149. The discharge 55 sides of the twin pumps are connected by conduits 150 and 151 to the pressure passages of control valve devices 152 and 153 respectively. The discharge passages of these valve devices are connected by conduits 154 and 155 to a discharge line 156 leading back to the tank. 60 The control devices have bores containing the usual control valves 157, 158 and 159, 160 and these valves have suitable conveniently located control handles. The bores containing the valves 157 and 159 are connected by conduits 161, 162 and 163, 164 to the opposite ends 65 of the rear jack cylinders 134. The bores containing the valves 158 and 160 are connected by conduits 165, 166 and 167, 168 to the opposite sides of the reversible, variable speed hydraulic motors or engines 169 for independently driving the crawler treads 15. The discharge side of the small pump 145 is connected by a conduit 170 to a control valve device 171 having bores containing the usual control valves 172 and 173, likewise having conveniently located operating handles. The discharge passage of this valve device is connected by 70

conduit 174 to the return line 156 leading back to the tank.

Leading from the pressure passages of the valve device 152 and 153 are conduits 175 and 176 connected to a pressure line 177 leading to the pressure passage of a control valve device 178, the latter having bores containing the usual control valves 180, 181, 182 and 183 and these control valves likewise have conveniently located control handles. The discharge passage of the valve device 178 is connected by a conduit 184 to the discharge line 156 leading back to the tank. The bores containing the valves 181 and 182 are connected by conduits 185, 186, and 187, 188 to the opposite ends of the front jack cylinders 133 while the bore containing the valve 183 is connected by branched conduits 189 and 190 leading to the opposite ends of the feed or sump cylinders 128. Conduits 191 and 192 may lead from the conduits 189 and 190 to the opposite ends of the holding column 135. A telescopic cylinder and piston arrangement or so-called "trombone" structure is provided for eliminating some of the flexible conduits and, in this instance, comprises a series of tubular conduits or cylinders 195 secured to the base frame 2 and connected to the control valve devices 171 and 178. Conduits or tubes 196 are secured to a transverse block or manifold 197 connected, as by brackets 198, to the sliding support 4 and these conduits extend through suitable packings at the opposite ends of the cylinders 195 and are closed at their rear ends by suitable plugs 201. Ports in the tubular conduits 196 connect the interior of the latter with the bores of the cylinders 195 and the forward ends of the conduits are connected to passages in the block 197. It will thus be seen that irrespective of the position of the sliding support along its guideways relative to the base frame fluid may be supplied through the cylinders 195 and tubes 196 to the passages in the block 197, while constant volume is maintained. The bore containing the valve 172 is connected by conduits 205 and 206 leading to two of the cylinders 195 respectively and the passages in the manifold 197 are connected by conduits 207 and 208 to the opposite sides of the reversible hydraulic motor 106 for driving the conveyor. The bore containing the valve 173 is connected by a conduit 209 to another of the cylinders 195 and through a conduit 210 connected to the manifold 197 and branch conduits 211 and 212 to the cylinders 119 (Fig. 12) of a hydraulic tension release mechanism for the belt conveyor. The bore containing the valve 180 of the valve device 178 is connected by a conduit 213 to another of the cylinders 195 and through the passage of the manifold 197 to a conduit 214 and branch conduits 215 and 216 to the cylinders 85 of the swing cylinder devices 7. The hydraulic system above described is provided with the usual overload release valves, pressure-reducing valves, check valves, etc. and since these are conventional in such systems they are not described in detail herein.

The control handles for the various control valves and the control elements for the several electric motors are compactly arranged at the rear end of the base, so that the operator may control the machine while standing in back of the machine, in a convenient manner.

The general mode of operation of the improved continuous mining machine is as follows: The machine may be propelled and steered as it travels about the mine by the crawler treads 15 driven by the motors 169 which are controlled by the valves 158 and 160 of the valve devices 152 and 153. As shown diagrammatically in Fig. 13, the machine is designed to travel along a longwall coal face designated L and as the disintegrating head is operated to dislodge and disintegrate the coal, the disintegrated coal is moved rearwardly from the face by the top runs of the disintegrating chains and is discharged onto the cross conveyor 8 which in turn discharges the disintegrated coal laterally from the machine onto a face conveyor F arranged in parallelism with the face. Roof props or safety posts P support the roof at the face, and as mining progresses the face conveyor may be extended along the face at the face sides of the roof props or posts. The machine is designed to operate in either direction along the coal face.

When the machine is in operating position at the face, as shown diagrammatically in Fig. 14, the disintegrating head may swing downwardly about its pivot 5 by venting liquid from the cylinders 85 of the swing cylinder devices 7, under the control of the control valve 180 until the outer nose or tip end of the head is disposed at the floor level, as indicated in dotted lines at A in Fig. 14.

Liquid may then be trapped in the cylinders 85 under the control of the valve 180 to lock the head against swinging movement, and the valve 183 may then be manipulated to supply liquid under pressure to feed cylinders 128 which slide the support 4 rectilinearly forwardly along its guides relative to the base frame 2 to sump the outer nose portion of the head into the coal at the floor level, as indicated in dotted lines at B in Fig. 14. The valve 183 may then be positioned to trap liquid in the cylinders 128 to hold the sliding support in position against movement relative to the base and the valve 180 may be manipulated to effect supply of liquid under pressure to the cylinders 85 of the swing devices 7 to swing the head upwardly about its pivot. As the head is swung upwardly the disintegrating chains tear away the coal in relatively large lumps from the solid coal seam and disintegrate the coal and convey the disintegrated coal along the top of the head to the cross conveyor 8. When the nose or tip end of the head reaches the roof level, as indicated in dotted lines at C in Fig. 14, the valve 180 may be positioned to trap liquid in the swing cylinders 85 to hold the head against swinging movement and the valve 183 may again be positioned to effect liquid supply to feed cylinders 128 to retract the support 4 rectilinearly along its guides relative to the base to withdraw the headnose from the face to the position indicated in dotted lines at D in Fig. 14. These positioning, sumping, swinging and withdrawal operations are rapidly repeated during operation of the machine so that the coal is rapidly mined and loaded out. The machine is, of course, advanced between each disintegrating cycle by the treads of the crawler base. The valves 157 and 159 of the valve devices 152 and 153 and the valves 181 and 182 of the valve device 178 may be positioned to effect supply of liquid pressure to the floor jack cylinders 133 and 134 to vary the tilted position of the base frame with respect to the horizontal thereby to enable guiding of the disintegrating head at the proper angle with respect to the floor or pavement during the sumping operation. When the machine is operated along a longwall face having a steep gradient, it is desirable to start the machine at the top of the face and to proceed downwardly, and the holding column 135, also controlled by the valve 183, may be set up between the floor and roof to hold the base stationary during the sumping, swinging and withdrawal operations of the disintegrating head, and this holding column may be released each time the machine is advanced by the treads. The conveyor driving motor 106 may be controlled by the valve 172 to effect conveyor drive in the desired direction. During the sumping and withdrawal operations of the head the motors 9 remain stationary with the base frame while the head is driven through the universal telescopic shaft connections 10, eliminating radical shifting of the center of gravity thereby resulting in better machine-balance. The telescopic cylinder and tube conduit or so-called "trombone" arrangement provides for constant liquid volume as the cylinders and tubes are extended and collapsed during the rectilinear movements of the head, and by their provision numerous flexible conduits have been eliminated. Since the general mode of operation of the continuous miner of this application is fully disclosed in the copending ap-

lication Serial No. 131,094, above referred to, further discussion thereof is herein considered unnecessary.

As a result of this invention, an improved continuous mining apparatus is provided which is especially designed for use in the mining of coal in accordance with the long-wall system. The novel disintegrating head structure embodying the improved diverging arrangement of the disintegrating chains substantially improves the removal of coal from the solid, resulting in more rapid production of relatively coarse coal. By the provision of the individual adjusting devices for the disintegrating chains the obtaining of the proper chain tension is facilitated. The machine is compact and well balanced, capable of operating on steeply inclined grades, and is readily maneuverable. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a continuous mining apparatus, a coal disintegrating mechanism for dislodging coal from a solid coal seam comprising a swingable head frame having a series of guideways and an outer coal-engaging portion, and endless disintegrating chains guided for orbital circulation along said guideways, said chains adapted to flex in angularly related planes, said guideways having parallel forward and rearward portions, and intermediate portions diverging forwardly away from the head pivot, said rearward portions of said guideways being parallel with said forward portions but spaced closer together whereby the outer coal-engaging portion of said head is substantially wider than its pivoted rear portion.

2. A disintegrating head mechanism for a continuous mining apparatus comprising a swingable head frame having guideways with portions of said guideways diverging forwardly and outwardly away from the head pivot, and orbitally movable disintegrating chains adapted to flex in angularly related planes and guided for circulation about said guideways, the outer portions of said guideways lying in a common zone extending transversely of said head frame so that the outer end of the head mechanism lies in a straight line parallel to the pivotal axis of said head frame.

3. A disintegrating head mechanism as set forth in claim 2 wherein said guideways have adjusting means individual to each chain and respectively engaging the latter for individually placing said chains under the proper tension.

4. A disintegrating head mechanism as set forth in claim 2 wherein said head frame has a nose provided with individual nose pieces guided on said frame and which are independently adjustable to vary the tension of each chain, and individual adjusting devices are provided for said nose pieces for independently adjusting the latter.

5. A disintegrating head mechanism for a continuous mining apparatus comprising a head frame provided to swing in vertical planes and the outer transverse portion of the head mechanism lying in a straight line parallel to the pivotal axis of said head frame, said head frame having chain guideways which diverge forwardly and outwardly from the head pivot, and universal disintegrating chains each having chain elements and universal pivotal connections between said chain elements whereby the chains may flex in angularly related planes, said chains being guided for orbital movement along said guideways.

6. A disintegrating head mechanism as set forth in claim 5 wherein said head frame is provided with an outer nose and said chain guideways have guiding portions on said nose extending in parallel longitudinal vertical planes,

said guiding portions of said nose as said chains pass around said guiding portions of said nose guiding the outer portions of said chains in parallel longitudinal vertical planes, and said chains extending rearwardly from their outer portions along lines which converge rearwardly.

5 7. A disintegrating head mechanism as set forth in claim 6 wherein said guideways at the rearward portion of said head frame have guiding portions parallel with said guiding portions of said nose which direct the rearward portions of said chains along parallel longitudinal vertical paths as they pass about the head frame pivot.

10 8. A disintegrating head mechanism for a continuous mining apparatus for dislodging coal from a solid coal seam comprising a support, a head frame pivotally mounted on said support to swing in vertical planes and providing guideways, endless disintegrating chains adapted to flex in angularly related planes and guided for orbital movement along said guideways, said head having said guideways and said chains arranged with portions extending along lines converging rearwardly from the forward portion of said head mechanism to provide a relatively wide forward coal-engaging portion lying in a straight line parallel with the pivotal axis of said head frame, and a narrower rearward pivoted end portion, and extensible power swing devices mounted on said support at the sides of said narrow head portion within the rearward projection of the lateral limits of said wide forward portion for swinging said head frame about its pivot.

15 9. A disintegrating head mechanism as set forth in claim 8 wherein said power swing devices are pivotally mounted on said support to swing in vertical planes about aligned axes parallel with the head frame pivot axis, and each comprising a pair of coaxial parallel cylinders arranged side by side in a common longitudinal zone and respectively containing reciprocable pistons movable in unison, and said pistons having pivotal connection with said head frame on aligned axes parallel with said cylinder pivot axes.

20 10. A disintegrating head mechanism for a continuous mining apparatus for dislodging coal from a solid coal seam comprising a head frame pivoted to swing in vertical planes and having an adjustable nose, said head frame providing a series of guideways, a series of endless disintegrating chains guided for circulation along said guideways, said guideways having intermediate portions diverging forwardly away from the frame pivot and said chains moving along said guide portions and about said nose, a series of swingable coal guiding and directing members pivoted to swing in common planes extending transversely of said head frame, said swingable members disposed intermediate said guideways at the top of said head frame, means for adjusting said nose relative to said head frame, and connections between said nose and said coal guiding and directing members for effecting swinging of the latter into different angular positions about their pivots as said nose is adjusted.

25 11. A disintegrating head mechanism as set forth in claim 10 wherein said coal guiding and directing members are longitudinally slotted at their forward portions and screws are secured to said nose and passed through said slots, said slots being inclined with respect to the path of adjustment of said nose relative to said head frame whereby nose adjustment effects swinging of said members.

30 12. A disintegrating head mechanism for dislodging coal from a solid coal seam comprising a head frame pivoted to swing in vertical planes and having an adjustable outer nose and guiding means including a series of guideways, a series of disintegrating chains movable in orbital paths relative to said guiding means including movement along said guideways and about said nose, and a series of relatively adjustable nose pieces guided in said nose, one nose piece individual to each chain, means for adjusting said nose, and means for individually ad-

11

justing said nose pieces, said guideways having portions diverging forwardly away from the head pivot and said chains each comprising a series of links and means for universally pivotally connecting said links, said guiding means including said guideways constructed and arranged to cause said chains to flex in angularly related planes as they travel along said guideways.
